UNITED STATES PATENT OFFICE.

HIRAM T. BUSH, OF DETROIT, MICHIGAN.

DESIGN FOR A LATCH-KEEPER.

SPECIFICATION forming part of Design No. 33,946, dated January 22, 1901.

Application filed December 26, 1900. Serial No. 41,166. Term of patent 7 years.

To all whom it may concern:

Be it known that I, HIRAM T. BUSH, a citizen of the United States, residing at Detroit, in the county of Wayne and State of Michigan, have invented and produced a certain new and original Design for a Latch-Keeper, of which the following is a specification, reference being had therein to the accompanying drawings, in which—

10 Figure 1 is a front elevation. Fig. 2 is a side elevation. Fig. 3 is a plan, and Fig. 4 is a perspective.

15 A is an oblong base-plate. B is a lug projecting outward from said plate and substantially A-shaped in side elevation. The front of the base portion of this lug is cut away to form a recess C, which also extends through the base-plate, the upper edge a of said recess being slightly inclined to the plane of 20 the base and forming the cross of the A. The apex of the lug forms a ridge b, and one of

the sides c is partially cut away by the recess C to form an edge d parallel to said ridge b. The rear wall of the lug is plain and slightly inclined from the perpendicular to the base- 25 plate.

The leading feature of the design is the plate having the substantially A-shaped lug projecting therefrom, the front of the base portion of said lug being recessed and the upper edge of said recess forming the cross of the A. 30

What I claim as my invention is—

The design for a latch-keeper, substantially as herein shown and described. 35

In testimony whereof I affix my signature in presence of two witnesses.

HIRAM T. BUSH.
